US00D876225S

(12) **United States Design Patent** (10) Patent No.: **US D876,225 S**
Vallotton et al. (45) Date of Patent: **** Feb. 25, 2020**

- (54) **CAP FOR PHARMACEUTICAL CONTAINERS**
- (71) Applicant: **B. Braun Melsungen AG**, Melsungen (DE)
- (72) Inventors: **Raphaël Vallotton**, Blonay (CH); **Michel Pittet**, Aumont/FR (CH)
- (73) Assignee: **B. Braun Melsungen AG** (DE)
- (**) Term: **15 Years**
- (21) Appl. No.: **29/685,475**
- (22) Filed: **Mar. 28, 2019**

- Related U.S. Application Data**
- (62) Division of application No. 29/600,128, filed on Apr. 10, 2017.
- (30) **Foreign Application Priority Data**
- Oct. 10, 2016 (EP) 003413541
- (51) **LOC (12) Cl.** **09-07**
- (52) **U.S. Cl.**
USPC **D9/435; D9/436**

(57) CLAIM

The ornamental design for a cap for pharmaceutical containers, as shown and described.

DESCRIPTION

FIG. 1 is a perspective view of a cap for pharmaceutical containers;
FIG. 2 is a top plan view thereof;
FIG. 3 is a bottom plan view thereof;
FIG. 4 is a front elevation view thereof;
FIG. 5 is a rear elevation view thereof;
FIG. 6 is an elevation view thereof from the right side; and,
FIG. 7 is an elevation view thereof from the left side.
The broken line showing of the cap for pharmaceutical containers is for the purpose of illustrating portions of the cap for pharmaceutical containers and forms no part of the claimed design.

1 Claim, 7 Drawing Sheets(56)
